US0D1060663S

(12) **United States Design Patent** (10) **Patent No.:** **US D1,060,663 S**
(45) **Date of Patent:** **** Feb. 4, 2025**

(54) **URINE COLLECTION DEVICE**

- (71) Applicant: **Sage Products, LLC**, Cary, IL (US)
(72) Inventors: **Brian J. Ecklund**, McHenry, IL (US);
Kristin M. Sexton, Lake in the Hills,
IL (US); **Alex D. Kea**, Chicago, IL
(US); **Daniel R. Ulreich**, Cary, IL (US)
(73) Assignee: **Sage Products, LLC**, Cary, IL (US)
(**) Term: **15 Years**
(21) Appl. No.: **29/948,997**
(22) Filed: **Jun. 25, 2024**

(57) **CLAIM**

The ornamental design for urine collection device as shown
and described.

DESCRIPTION

FIG. 1 is a perspective view of a urine collection device
showing our new design.

FIG. 2 is a top plan view of the urine collection device of
FIG. 1.

FIG. 3 is a bottom plan view of the urine collection device of
FIG. 1.

FIG. 4 is a first side elevation view of the urine collection
device of FIG. 1.

FIG. 5 is a second side elevation view of the urine collection
device of FIG. 1.

FIG. 6 is a third side elevation view of the urine collection
device of FIG. 1; and,

FIG. 7 is a fourth side elevation view of the urine collection
device of FIG. 1.

The portions of the drawing shown in broken lines represent
environmental aspects and form no part of the claimed
design.

1 Claim, 5 Drawing Sheets
